United States Patent

Des. 238,169
Patented Dec. 23, 1975

238,169

PAPER WEIGHT

Cecelia A. Bieringer, 100 Wilshire Drive,
Minnetonka, Minn. 55343

Filed Mar. 18, 1974, Ser. No. 451,842

Term of patent 14 years

Int. Cl. D19—02

U.S. CL. D19—96

Fig. 1

Fig. 2

Fig. 3

Fig. 4

FIG. 1 is a perspective view of a paper weight showing my new design;

FIG. 2 is a side elevational view thereof;

FIG. 3 is a top plan view thereof; and

FIG. 4 is a bottom plan view thereof.

A side elevational view from any other side is essentially identical to FIG. 2.

I claim:

The ornamental design for a paper weight, as shown and described.
